Primary Examiner — Nathan M Johnston(74) *Attorney, Agent, or Firm* — Borden Ladner Gervais LLP; Curtis B. Behmann(57) **CLAIM**

The ornamental design for a double hook, as shown and described.

DESCRIPTION

FIG. 1 is a front perspective view of a double hook showing the design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines show portions of the double hook that form no part of the claimed design.

1 Claim, 4 Drawing Sheets(56)
